UNITED STATES PATENT OFFICE.

GEORGE KRUSE, OF GEORGE, IOWA.

CROSSING SAFETY SIGNAL.

Application filed July 15, 1925. Serial No. 43,735.

This invention relates to a signaling device and particularly to a crossing signal for a railway especially adapted for rural districts where railways cross highways. A great loss of life occurs annually, through accidents at such rural railway crossings. It is impracticable from an expense standpoint to provide a watchman at such crossings and an automatic signal or some signal operated by the train is therefore very desirable at such crossings. The use of such a signal would unquestionably result in great conservation and saving of human life.

It is an object of this invention, therefore, to provide a simple and efficient form of crossing signal which normally is in inoperative position, which is arranged to move to operative position to indicate the approach of the train by the action of the train and which is also arranged to be moved to inoperative position by the train.

It is a further object of the invention to provide such a signal comprising a frame adapted to be disposed at the crossing, an arm carried by said frame adapted to swing to inoperative and operative positions, means normally tending to hold said arm in inoperative position, together with means adapted to be operated by the train for operating on said last mentioned means to permit said arm to move to operative position.

It is also an object to provide a signal device such as is set forth in the preceding paragraph, together with means also actuated by the train for acting on the means normally holding the signal in inoperative position to permit the same to move the signal to inoperative position.

It is still another object of the invention to provide a crossing signal comprising a frame, an arm swingable therein to inoperative vertical position or to operative horizontal position, a weight tending normally to hold said arm in vertical inoperative position, and means operated by the train for lifting said weight to permit said arm to move to horizontal operative position, said last mentioned means carrying a member adapted to operate a further means for initially urging said arm to move to its horizontal operative position.

It is still a further object of the invention to provide a device such as set forth in the preceding paragraph comprising resilient means disposed beneath said weight

and the means for lifting the same to absorb the shock transmitted to said parts by the action of the train.

It is still a further object of the invention to provide a crossing signal comprising a signal adapted to move from inoperative position to operative position, means operated by the train while going in one direction or the other for causing said signal to move to operative position, together with means operated by the train whether going in one direction or the other to restore said signal to inoperative position after the train reaches the crossing.

These and other objects and advantages of the invention will be fully set forth in the following description made in connection with the accompanying drawings in which like reference characters refer to the same parts throughout the different views, and in which,

Fig. 1 is a view in side elevation illustrating the device;

Fig. 2 is a plan view of the device;

Fig. 3 is a view in side elevation of a portion of the device; a part thereof being shown in different positions in dotted lines;

Fig. 4 is a view in vertical section on the line 4—4 of Fig. 3, as indicated by the arrows;

Fig. 5 is a view in side elevation of another portion of the device;

Fig. 6 is a plan view of the parts shown in Fig. 5;

Fig. 7 is a view in side elevation of one train operated part of the device;

Fig. 8 is a vertical section taken on the line 8—8 of Fig. 1, as indicated by the arrows; and

Fig. 9 is a horizontal section taken on the line 9—9 of Fig. 7, as indicated by the arrows, Figs. 3 to 9 being shown on an enlarged scale.

Referring to the drawings, particularly Figs. 1 and 2, a portion of a railroad track is shown comprising the rails 10 and cross ties 11, a highway being indicated by the dotted lines 12 crossing said railroad, the grade crossing being indicated as having planks or similar members 13 adjacent the rails 10. Disposed adjacent the crossing 13 at each side of the rails is a frame 14. This frame structure, as shown in Figs. 3 and 4, comprises spaced members or plates 14^a and a shaft 15 traverses said frame adjacent

its top and is journaled therein, being held in place by suitable nuts screwed onto the threaded ends thereof. An arm 16 is carried on the shaft 15 and forms a signal, the same being shown as having the word "Stop" thereon adjacent one end. The arm 16 extends at both sides of shaft 15 and is adapted to swing from a horizontal operative position shown in full lines in Fig. 3 to a substantially vertical inoperative position shown in dotted lines in said figure. A pinion 17 is secured to shaft 15 and engaged by a gear segment 18 therebeneath carried on a shaft 18^a similar to shaft 15, which segment has an arm connected by a flexible member shown as a chain 19, and a weight 20 guided for movement between the members 14^a and within a U-shaped casing 14^b secured thereto. The weight 20 acting through members 18 and 17 normally tends to hold the arms 16 in its inoperative position. The weight 20 has spaced passages 20^a therethrough in which are disposed headed bolts 21 held in place by cotter pins 22 extending therethrough and disposed in holes 20^b in the weight 20. Coiled compression springs 23 surround the bolts 21 between the bottom of weight 20 and the plate 24 through which said bolts also pass and below which their heads are disposed, said plate 24 being of the same cross-sectional size and shape as the weight 20 and being guided therewith in the casing 14^b. A lever 25 is provided carried on a pivot extending through members 14^a and 14^b and having its inner end disposed beneath the plate 24. Lever 25 is pivotally connected at its outer end to a link 26 which, in turn, is pivotally connected at its upper end to another lever 27 also pivoted on a bolt extending through members 14^a and equipped with bolts at its threaded ends holding it in place. The lever 27 at its inner end is pivotally connected to a curved link 28 which is, in turn, pivotally connected at its lower end to one end of a crank arm 29 carried on the shaft 30 journaled in the members 14^a and 14^b and projecting at one side of said members. The shaft 30 is also journaled in a small bracket 31 (Fig. 8) at one end of the frame members 14 and has a crank arm 32 adjacent its outer end. The crank arm 32 is pivotally connected to a link 33 which is, in turn, pivotally connected at its other end to a pivot member 34 (Fig. 9) shown as a rivet with its ends countersunk in the spaced sides of a lever 35, which lever is pivoted at its lower end in the center of a bracket 36 bolted to the underside of a pair of cross ties 11 by headed and nutted bolts 37 which also extend through the horizontal and outwardly extending flanges 38^a of a pair of spaced U-shaped brackets 38 bolted to the top of said cross ties 11. The lever 35 has disposed between its spaced arms and adjacent the

top thereof a stop member 39 having a flat horizontal top. A lever 40 is pivoted between the arms of lever 35 above stop 39 and has a laterally projecting arm 40^a engaging stop 39, said arm being held in engagement with said stop by a coiled tension spring 41 engaging said arms and also secured at its lower end to the link 33. The lever 40 has its vertical arm disposed adjacent one of the rails 10, as shown in Fig. 75. A link 42 is also pivotally connected to rivet 34 and extends parallel with the rails 10 at the outer side thereof through a suitable guide bracket 43 carrying spaced guide rollers 44, which bracket is secured to the cross ties 11 by suitable headed and nutted bolts. The other end of link 42 is threaded into the cylindrical and tapped end of a yoke 45 having a block 46 secured between the spaced ends thereof by a headed rivet, which block is pierced by the cylindrical threaded end of a link 49 having a stop nut 47 adapted to engage the outer end of block 46 and having a nut 48 adjacent its inner end, a coiled compression spring 50 being disposed between nut 48 and block 46 and surrounding link 49. The end of link 42 is provided with a jamb nut engaging the end of yoke 45. The other end of link 49 is pivotally connected to the lower end of a lever 50 comprising spaced sides, which lever is intermediately pivoted on a headed and nutted bolt 51 extending through the top central portion of a pair of U-shaped brackets 52 having outwardly extending lateral flanges secured to the cross ties 11 by suitable headed and nutted bolts. A block 53 is secured between the sides of lever 50 and has a projecting hook-shaped arm over which is secured the lower end of a coiled tension spring 54, the upper end of which is engaged over a laterally extending arm 55^a of a lever 55 similar to the lever 40. The arm 55^a is held against the top flat surface of a block 56 anchored between the sides of lever 50 by the spring 54. The structure above described, it will be seen, is duplicated at both sides of the track extending to the left at the bottom of Fig. 1, and extending to the right of frame 14 at the top of Fig. 1.

The bottom of each frame 14 is provided with a pair of holes through which extends vertically extending pins 58 connected to a cross bar 58^a. The cross bar 58^a normally rests upon a lever 59 pivoted between a pair of brackets 60 bolted to the bottom of frame 14 and depending therefrom. The brackets 60 are curved and carry therebetween adjacent their lower ends a roller 61. A longitudinally movable rod 62 rests upon the roller 61 and has a vertical arm 63 upstanding therefrom bifurcated at its upper end and provided with a cam roller 64 adapted to engage the curved underside of a lever 130

59. The rod 62 has an intermediate cylindrical portion which passes through a conduit 65 extending beneath the highway 12 into a pit 66 at the other side of the highway, 5 the portions 58 and 62 being also disposed in a pit 67^a. The rod 62 is pivotally connected at its other end with the lower end of a lever 67 which is intermediately pivoted in a bracket 68 disposed in pit 66 and depending from a plate 66^a at the side of the roadway opposite the frame 14. The lever 67 has a slotted upper end engaging a pin or screw 69 projecting from the outer end of a crank arm 70 secured to one end of a shaft 10 71 journaled in a pair of spaced bearings 72 bolted to the top of plate 66^a. The shaft 71 carries at its other end an arm 73, the outer end of which is connected to a link 74 similar in all respects to link 33. The other end of 15 link 74 is connected to the intermediate portion of a lever 75, said lever and parts carried thereby similar in all respects to the lever 35 and the parts carried thereby, already described, and pivoted to a bracket 20 76 similar in all respects to the bracket 36 already described and movable between a pair of brackets 77 similar in all respects to the bracket 38 already described. The lever 75 also has connected thereto a link 78 similar in all respects to link 42, which is also movable through one or more guide brackets 43 and between rollers 44 therein. The link 78 has a yoke 79 connected thereto similar in all respects to the yoke 45, which yoke is 25 connected, in the manner already described with a link 80 pivotally connected to the lower end of a lever 81 similar in all respects to the lever 50 and, like said lever 50, pivoted between a pair of brackets 81^a similar in all respects to the brackets 52, said lever 81 having a lever 82 at the top thereof similar in all respects to lever 55, already described. The structure from the link 74 to the lever 82 is 30 similar in all respects to the structure extending from link 33 to the lever 55 and need not be again specifically described. It will be seen from inspection of Fig. 1, that the parts designated from 74 to 82 are duplicated at opposite sides of the track, said structure being shown at the right hand of Fig. 1 and at the bottom thereof and also at the left hand of said figure at the top thereof.

An arm 83 (Fig. 3) is pivoted on a headed and nutted bolt or stud 83^b in one of the plates 14^a and has an auxiliary arm 83^a extending therefrom. The arm 83^a is adapted to engage one edge of the signal arm 16 at the recess 16^a therein when said arm begins its movement to horizontal position. The arm 83 is apertured to receive a pin 84 35 standing from and secured to one side of link 28 at its upper end, a coiled spring 85 surrounding said pin 84 between link 28 and arm 83. The arm 83 is also of sufficient width to be engaged by the upper end of a pin 86 extending upward from the upper side of weight 20, a spring 87 also surrounding pin 86 and adapted to engage the underside of arm 83. Pin 86 and spring 87 have 40 their upper portions broken away in Fig. 4, but are fully shown in Fig. 3.

In use, the signal arm 16 will normally be disposed in its vertical inoperative position and lever 55 will be in vertical position, as indicated in dotted lines in Fig. 3, lever 40 at this time being in its depressed or inclined position, such as occupied by lever 55 in Fig. 1. Levers 82 will also be disposed in vertical position and lever 75 in 45 inclined position, as shown in Fig. 1. Weight 20 will be in its lower position and levers 25 and pins 58 will be disposed below the weight and below plate 24. Should a train approach the crossing from the direction at the left hand end of Figs. 1 and 2, the locomotive tender or the cars will be provided with a plate or dog adapted to engage the upstanding lever 55. This lever will be then knocked forward to the inclined position shown in Fig. 1 and this will pull upon links 49, 42 and 33 so that arm 32 is rotated, as is shaft 30. This 50 swings arm 29 and pushes up on link 28. This action swings the outer end of levers 27 and 25 down and the inner end of lever 25 is raised and lifts plate 24. The plate 24 is moved upwardly, the shock of the impact being relieved and absorbed by the spring 23 which will be moved upwardly 55 and move weight 20 upwardly. Weight 20 being lifted the tension is taken off from chain 19 and arm 16 will be free to drop, owing to the heavy signal end thereof being disposed at one side of the vertical, to its horizontal position, as shown in Fig. 3. As link 28 is pushed upwardly, the spring 85 is pushed upwardly against arm 83 so that this arm is swung upwardly and its auxiliary arm 83^a engages the edge of arm 16 in 60 the recess 16^a and gives the arm a push or kick so that it will be sure to fall to its horizontal position. The signal is now placed in operative position to indicate the approach of a train. When the train has reached the crossing and the locomotive is part way across the crossing the dog or plate thereon will engage the lever 40 which was movable to its vertical position by the link 42. The lever 55 will be placed a 65 long distance from the crossing so that the train will have passed this lever before it engages lever 40. When the lever 40 is engaged the links 49, 42 and 33 will be moved in the opposite direction or toward frame 14. This will pull down on link 28 and the inner end of the lever 25 will be depressed so that weight 20 and plate 24 are again free to drop and through the chain 19 and gears 18 and 17, swing the 70

signal arms 16 to inoperative position. As the train continues on across the crossing, it will pass over the arm 75 and will engage the lever 82. Said lever 82, however, will merely swing and extend the spring thereon which is similar to the spring 54 and will be pulled back to its position by said spring after the engine passes. As the train approached the crossing as described, it also engaged the lever 82 which is on the opposite side of the rails from the lever 55. This action moved links 80, 78 and 74 away from plate 67 and rotated shaft 71 seen at the upper left hand side of Fig. 2. This caused a push on the rod 62 at the upper side of Fig. 2, which extends beneath the highway and roller 64 on arm 62 traveled beneath lever 59 and raised the same. Block 58^a and pins 58 were thus raised and block 24, weight 20 were elevated, as already described in connection with lever 25. The signal arm 16 at the opposite side of the track was also thus allowed to drop to horizontal position. When weight 20 was raised, a spring 87 on rod 86 engaged the underside of arm 83 and the auxiliary arm 83^a thereof gave a push or kick on the lower end of signal 16, insuring that the same would drop to horizontal position. The signal at both sides of the crossing was thus operated by the train approaching from the left of Fig. 1. After the train passed arm 82 and was midway on the crossing arm 75 would be operated and this would move links 74, 78 and 80 toward plate 66^a. This causes a longitudinal movement of rod 62 in the opposite direction to that already described so that arm 83 and roller 64 are withdrawn from beneath lever 59. Pins 58 and bar 58^a then drop and permit weight 20 and its plate 24 again to drop and, through the segment 18 and pinion 17 again to raise the signal arm 16 to inoperative position. The signals at both sides of the crossing are thus moved to inoperative position after the train has reached the crossing.

The parts being duplicated at each side of the crossing the signals would be operated in the manner similar to that already described by a train coming from the right, as shown in Figs. 1 and 2. It will be noted that if the levers 40, 75 or 82 are engaged by a train coming in the opposite direction from that in which they are supposed to operate, the springs 41 and 54 will yield so that no damage will be done. As stated, the shock on the parts by the engagement of the train is absorbed by the springs 23 and also by the springs 50. The provision of the swinging arm 83 insures that the signals will always drop to their operative position to warn traffic on a highway that a train is approaching. The springs 85 and 87 also relieve excessive shock on the arm 83 and on the signal arm 16. Ample provision is thus made

for absorbing the shock, due to the impact of the train so that the parts will operate without any danger of being broken.

From the above description it is seen that applicant has provided a very simple and highly efficient grade crossing signal. The parts are comparatively few in number simply and ruggedly made so that they will be very durable and when once installed, the device will need no attention and will operate practically indefinitely. The use of such a signal will unquestionably result in prevention of many accidents. The signaling arm, of course, can be variously made and, if desired, provided with illuminating devices. The operating parts will, in practice, be provided with protecting casings (not shown) so that ice or snow will not accumulate thereon and interfere with the operation thereof. The actual construction of the parts has been amply demonstrated in actual use and found to be very successful and efficient.

It will, of course, be understood, that various changes may be made in the form details, arrangement and proportions of the parts without departing from the scope of applicant's invention, which, generally stated, consists in a device capable of carrying out the objects above set forth, in the novel parts and combinations of parts disclosed and defined in the appended claims.

What is claimed is:

1. A railway crossing signal having in combination, a frame disposed at one side of the roadway, an arm forming a signal pivoted in said frame adapted to swing to substantially vertical inoperative position and adapted automatically to swing to substantially horizontal operative position, a weight operatively connected to said arm normally holding the same in inoperative position and means disposed in position to be operated by a dog on the engine tender or cars for engaging and lifting said weight and permitting said arm to move to operative position.

2. The structure set forth in claim 1, said last mentioned means carrying a member adapted to engage said arm and initially urge the same to its operative position.

3. A railway crossing signal having in combination, a frame disposed at one side of the roadway, an arm forming a signal, a pivot shaft carrying said arm, a second shaft geared to said pivot shaft, a weight normally tending to turn said second shaft and pivot shaft to hold said arm in substantially vertical inoperative position, a member disposed beneath said weight, lever means for moving said member to raise said weight to permit said arm to move to substantially horizontal operative position, and a member disposed adjacent the railway track adapted to be engaged by a dog on an engine or car to actuate said lever mechanism.

4. The structure set forth in claim 3, and

springs disposed beneath said member between said member and weight to absorb the shock when said member is raised.

5. The structure set forth in claim 3, and means carried by said weight for giving said arm an initial impulse to move to substantially horizontal position when said weight is raised.

6. A crossing signal having in combination, a frame disposed at one side of the highway and comprising spaced members, a shaft extending between said members, a signal carried by said shaft and swingable to substantially vertical inoperative position and substantially horizontal operative position, a weight guided for movement in said frame, means connecting said weight to said signal whereby said weight normally tends to hold said signal in its inoperative position, means for lifting said weight to permit said signal to move to operative position, resilient means disposed between said last mentioned means and said weight adapted to relieve the shock on said weight and a member disposed a considerable distance from said frame adjacent the track adapted to be operated by a train and operatively connected to said means for lifting said weight whereby when said member is operated by a train said weight will be lifted and said signal will move to operative position.

7. The structure set forth in claim 6, said means connecting said signal and weight comprising a pinion secured to said shaft, a gear segment meshing with said pinion and a flexible means connecting said weight and segment.

8. A crossing signal having in combination, a frame disposed at one side of the highway and comprising spaced members, a shaft extending between said members, a signal carried by said shaft and swingable to substantially vertical inoperative position and substantially horizontal operative position, a weight guided for movement in said frame, means connecting said weight to said signal whereby said weight normally tends to hold said signal in its inoperative position, a lever journaled in said frame having one end disposed beneath said weight, resilient means disposed between the end of said lever and said weight, a second lever pivoted in said frame connected to the other end of said first mentioned lever, and means adapted to be operated by the train going in one direction connected to said second mentioned lever whereby when said last mentioned

means is operated said first mentioned lever will be moved to lift said weight and permit said signal to move to operative position. 60

9. The structure set forth in claim 8, means pivoted in said frame adapted to engage said signal in its initial movement to operative position and urge the same toward its operative position, and means connected 65 to said second mentioned lever for operating said last mentioned means.

10. The structure set forth in claim 8, a third lever disposed beneath said weight and adapted to raise the same, a member adapted 70 to be engaged and operated by a train going in the opposite direction, operatively connected to said third lever for raising said weight and permitting said signal to move to operative position. 75

11. The structure set forth in claim 8, a third lever disposed beneath said weight and adapted to raise the same, a member adapted to be engaged and operated by a train going 80 in the opposite direction, operatively connected to said third lever for raising said weight and permitting said signal to move to operative position, means pivoted in said frame and adapted to engage said signal in its initial movement to operative position 85 and urge it toward operative position, and a member carried by said weight for engaging said last mentioned means when said weight is lifted.

12. A crossing signal having in combination, a frame disposed at one side of the highway, an arm pivoted in said frame forming a signal and adapted to swing to substantially vertical inoperative position and substantially horizontal operative position 90 and a weight connected to said arm normally tending to swing the same to inoperative position, a lever having one end disposed under said weight, means adapted to be engaged by a train going in one direction connected to said lever for operating said lever to lift said weight and permit said signal to move to operative position, a second lever disposed beneath said weight and adapted to lift the same, a cam disposed beneath said second mentioned lever, and means operated by a train going in the opposite direction for moving said cam and lift said second lever to lift said weight 100 and permit said signal to move to operative 105 position. 110

In testimony whereof I affix my signature.

GEORGE KRUSE.
